CARRYING CASE FOR A SHAVER

Norman Thomas Sanders, Mappleborough Green, Studley, England, assignor to Needle Industries Limited, Birmingham, England, a company of Great Britain

Filed July 25, 1962, Ser. No. 71,043

Term of patent 14 years

(Cl. D22—3)

Fig. 1

Fig. 2

Fig. 3

Fig. 4.

Fig. 5.

FIG. 1 is a side elevational view of a carrying case for a shaver showing my new design;

FIG. 2 is an end elevational view thereof;

FIG. 3 is a top plan view;

FIG. 4 is a bottom plan view; and

FIG. 5 is a perspective view thereof.

I claim:

The ornamental design for carrying case for a shaver, substantially as shown.
